UNITED STATES PATENT OFFICE.

HOWARD S. HART, OF NEW BRITAIN, CONNECTICUT.

FOOD-CUTTER.

No. 807,379.

Specification of Letters Patent.

Patented Dec. 12, 1905.

Application filed May 10, 1904. Serial No. 207,198.

To all whom it may concern:

Be it known that I, HOWARD S. HART, a citizen of the United States, residing at New Britain, county of Hartford, Connecticut, have invented certain new and useful Improvements 5 in Food-Cutters, of which the following is a full, clear, and exact description.

My invention relates to improvements in metal manufactures, and particularly food-10 cutters and similar constructions.

The object of my invention is to improve the construction of mechanism of this character by giving increased strength to the parts, providing a more economical method of construction and general efficiency of operation. 15

The adaptation of my invention resides particularly in those portions of a cutter known as the "casing," the "standard," and the "knife" and their co-operation.

20 It consists in constructing these parts of sheet metal, which is reinforced and strengthened by the method of construction and which provides efficiency of operation.

In the accompanying two sheets of drawings 25 I have illustrated those portions of a food-cutter which embody the principles of my invention.

Figure 1 is a side elevation of a food-cutter embodying the improvements of my invention. Fig. 2 is an end elevation of the same, showing the knife in position, but omitting the rotary cutter, the forcer, and the clamp. Fig. 3 shows the approximate form of a blank of sheet metal for forming the main 30 body or casing portion of the apparatus. Fig. 4 is a similar view of a blank for forming the support or standard. Fig. 5 shows the knife. Fig. 6 is a longitudinal vertical section of the casing and showing the forcer in side elevation. 40

The main elements of the construction are the casing or body portion 1; the standard or support 2; the clamp 3 for securing it to a table, &c.; the shaft 4, with a screw or forcer 45 for moving the mass of material; the perforated knife 5, having suitable cutting edges; the rotary cutter 6, having suitable blades, and the lock-nut 7.

The casing is formed from a blank of sheet 50 metal, approximately as shown in Fig. 3. The two opposite sides are shaped appropriately for forming the two sides 10 and 11 of the hopper, the side 10 being the larger to provide an approach to the forcer, which is mounted on the shaft 4. The forcer is of any suitable construction. One end of the blank is

formed into a flange 12 for attachment in a suitable manner to the standard. Before the sides of the casing are bent up a series of corrugations 13 are formed and arranged spirally 60 in the body to assist in the feeding action of the forcer. These corrugations materially increase the strength of the casing. The blank must of course be suitably dimensioned to provide for the metal which is used to form the corrugations and the hopper. The two edges of the blank when formed into the casing are secured together in suitable manner—as, for instance, by riveting. The joint being at the top, there is no danger of the juices of meat, &c., being lost. 70 The end of the casing opposite the standard provides a support for the knife 5. This support is preferably formed by enlarging the diameter of the casing at this point. This forms a shoulder 15, against which the knife 75 rests. 16 is a lug preferably made from the material of the casing and bent inward into a recess in the outer edge of the knife to prevent the knife from rotating relatively to the casing. The main upright member of the 80 standard is preferably reinforced by a corrugation 20. The upper end 21 of the standard is formed suitably to correspond with and support the left-hand end of the casing 12. A part is cut out to form the knife 5. The 85 flange of the casing may be riveted or otherwise suitably secured to the standard. The lower end 22 of the standard is bent inwardly to form a support for the clamp-screw 3, while the two side arms of the standard are bent 90 inward to form feet 23 23 for resting on the top of a table or similar construction. These feet are reinforced by corrugations 24 24. As a simple means for clamping the standard to a table or other structure I have provided the 95 clamp-screw 3 with a handle 30 and head 31. 32 is a screw-threaded plug which is secured to the lower arm 22 of the standard for holding the screw. 100

The forcer or screw is of any suitable construction and may be driven by a handle or wheel on the end 40. I have preferably formed the left-hand end of the forcer with a shoulder 41, which is of a size to correspond with the opening in the standard-plate. The 105 portion which is cut out from the standard is used to form the knife 5. The diameter of this knife is slightly greater than the inside diameter of the casing, as above mentioned. The opening in the standard is therefore of 110 larger diameter than the inside diameter of the casing, leaving a shoulder formed by the

smaller diameter of the flange 12 around the same when assembled. This shoulder afforded by the left-hand flange 12 of the casing forms an abutment for the shoulder 41 of the 5 forcer, so as to hold the forcer from movement in that direction. The pressure of the material which is being cut as it passes from the casing tends to react and move the forcer to the left, thus relieving the forcer at the 10 left-hand end of all friction except that eccentric pressure occasioned by the driving power applied. The cutter 6 is held securely in position by the set-nut 7. The resistance of the material passing through the openings 15 50 and between the knife and the cutter tends to separate them, so as to seat the knife and move the cutter outward. The pressure due to the rotation of the forcer tends to move it to the left, while the pressure due to the cutting of the material tends to move the cutter to the right. These counterbalancing forces hold the knife securely in place on its seat. The knife, however, being free to move, slightly yields to the cutter, so as to coöperate 20 with it in whichever direction either one wears, so as always to afford uniform cutting edges.

The parts are readily disassembled by simply moving the set-nut 7, when the forcer 30 may be withdrawn to the left. The parts are assembled by introducing the forcer into the casing, putting the knife in place, slipping the cutter 6 over the end of the forcer-shaft, and securing the parts together by the set- 35 nut 7.

What I claim is—

1. In a food-cutter, a casing formed from a single blank of sheet metal having its sides formed upwardly into a hopper and united at 40 its upper ends at the side of the hopper, its body having spirally-formed corrugations, an annular flange at one end, a standard having an annular flange riveted to said casing-flange and means at the other end for mounting a 45 knife and cutter.

2. In a food-chopper the combination of a casing having a hopper, a standard formed of sheet metal and having an opening surrounded by an annular flange secured to one end of 50 said casing, a forcer extending through the

opening in said standard, a knife mounted in the end of said casing opposite said standard and concentric with said forcer, said knife being at least as small as and so constructed that it may be formed of the sheet metal cut out 55 from the standard portion to form the opening for said forcer.

3. A food-chopper comprising the combination of a casing having an annular flange at one end, a forcer, a knife, a cutter and a standard for supporting said parts formed from a separate blank of sheet metal having an annular flange secured to said casing-flange and having a reinforced main arm with means for clamping and a pair of inwardly-turned reinforced feet for the purpose specified. 60 65

4. A casing for a food-cutter formed from a single blank of sheet metal, and comprising a substantially cylindrical body portion having an annular flange at each end, the edges 70 of the blank being brought together and united at the top of said cylindrical portion only, and a hopper portion integral with the body portion intermediate the ends thereof, and opening upwardly, said flanges affording 75 means for mounting a knife and for the attachment of a standard in combination with a knife arranged at one end and a standard arranged at the other end of said body portion.

5. A food-cutter comprising the combination of a casing, having a substantially cylindrical body portion and an open-mouthed hopper, an annular flange at one end of the body portion, a forcer mounted to rotate in the body portion and having a hub projecting 80 from the flanged end of the casing, a knife and a cutter at the opposite end, a standard formed of sheet metal and having an annular portion secured to the flanged portion of said body through which the hub projects, and 85 three downwardly-extending vertically-reinforced legs with laterally-extending feet, and clamping means for the purpose specified.

Signed at New Britain, Connecticut, this 7th day of May, 1905.

HOWARD S. HART.
